United States Patent Office

ROBERT WERNER, OF HOBOKEN, NEW JERSEY.

Design No. 4,500, dated November 29, 1870.

DESIGN FOR DRESS-TRIMMINGS.

The Schedule referred to in these Letters Patent and making part of the same.

To all whom it may concern:

Be it known that I, ROBERT WERNER, of Hoboken, in the county of Hudson and State of New Jersey, have invented a new and original Design for Dress-Trimmings; and I do hereby declare that the following is a full, clear, and exact description thereof, which will enable others skilled in the art to make and use the same, reference being had to the accompanying drawing forming part of this specification, in which—

Similar letters of reference indicate corresponding parts.

This invention relates to a new design for ruffl trimmings.

I make the middle row a of ruffles or folds, V-shape with greater or lesser regularity, as indicated in fig. 1.

The border folds b are lateral, as shown.

The trimmings may be single, as shown, or may have a series of rows, a , separated from each other rows, b , and may be of suitable color or colors.

I claim as my invention—

The central ruffles V, border ruffles b b , and trimmings a , combined, to form a design for ruffled trimmings.
